HUGH WATSON AND CHARLES M. WHRITENOUR, OF PATERSON, NEW JERSEY.

BEAMING ATTACHMENT FOR WARPING AND BEAMING MACHINES.

1,153,528.

Specification of Letters Patent. Patented Sept. 14, 1915.

Application filed June 3, 1914. Serial No. 842,565.

To all whom it may concern:

Be it known that we, HUGH WATSON and CHARLES M. WHRITENOUR, citizens of the United States, residing at Paterson, in the county of Passaic and State of New Jersey, have invented certain new and useful Improvements in Beaming Attachments for Warping and Beaming Machines, of which the following is a specification.

It is well known that in preparing certain kinds of warps the most perfect results cannot be obtained unless during the operation of winding on the reel the warp is subjected to a lateral traverse and during the operation of removing the warp from the reel and winding it on the beam it is subjected to a compensating or reverse traverse. So far as we are aware this treatment has heretofore only been applied in the preparing of warps for broad goods, the warp being first wound on the reel in sections, one after another, each as it is wound undergoing traverse, and then removed and wound on the beam all at once, while subjected to the compensating or reverse traverse.

The object of this invention is to provide a warping machine of the kind adapted to wind sections of warp on the reel thereof and simultaneously subject such sections to traverse with an attachment whereby such sections may be beamed not only on individual beams but subject to the compensating or reverse traverse, whereby ribbon or similar narrow-ware warps may be prepared (warped and beamed) subject to traverse. This object we have accomplished in and by the mechanism herein shown and described in such a way that warps of various widths and spacing may be accommodated in the machine.

In the accompanying drawings, Figure 1 is a side elevation of the beaming end of a warping machine of the so-called Swiss type (i. e., adapted for traverse) provided with the improved beaming attachment; Fig. 2 is a plan view of said attachment; Fig. 3 is a front elevation of the right-hand end thereof, partly in section; Fig. 4 is a vertical sectional view on line $x-x$ of Fig. 3; and, Figs. 5 and 6 show modifications.

a is the frame and b the reel of the machine which, it will be understood, has the usual reed-supporting carriage and means for transmitting a traverse motion laterally thereto (not shown).

c designates stands arranged on the beaming end of the frame and connected by the pairs of parallel fixed bars d , thus forming the framework of the aforesaid attachment. In the stands are journaled, parallel with the bars d , the splined shafts e and the screws or worms f . The reel b is driven from the main drive shaft g , journaled in one of said stands, through the usual belt h extending around pulleys i and j , the former of which is arranged on said shaft g and the latter of which is shiftable into contact with a friction wheel or pulley on the reel, all according to the usual construction; the splined shafts e , which are connected by gearing k , are driven in a well known manner through gearing (shown dotted in Fig. 1) from the drive shaft g through a disconnetive clutch connection generally indicated by l ; and the screws or worms are driven from the reel, at this time turning under the draft of the warps as they are wound on the rotating beams, through the sprocket and chain connections generally indicated by m .

n designates the beams, of which there are a suitable number, according to the width and spacing of the warps to be wound thereon, for each pair of guide-bars d , the two sets of beams being staggered so that the beams in each set will be opposite the spaces between those of the other. The means for supporting and transmitting rotary motion to each beam consists of a pair of brackets o and p and gearing housed in the bracket p and consisting of the toothed member q disconnetively clutched with the beam and the toothed member r meshing with member q and having a feather r' engaged in the spline of the corresponding shaft e .

The several brackets for each set of beams are directly penetrated by and arranged to slide on the rearward one of the corresponding bars d ; at the front, however, (referring to Figs. 2, 3, 4 and 5) an integral clamp s of each bracket grips a hollow shaft or sleeve t which is common to all the brackets for one of the sets of beams, forms with them a supporting structure for the beams and is fitted over and slides on the front bar d . The clamp of each bracket is operated by a set screw u , enabling the several brackets to be arranged in any desired spacing with reference to the hollow shaft t .

For accomplishing the traverse of each

set of beams and permitting the same to be set back by hand following each traverse we provide liberative means for connecting the structure (including each sleeve t and corresponding brackets) with the rotating screw or worm f . In Figs. 2, 3 and 4 this consists of a worm-wheel v meshing with said worm or screw and adapted to stand either held from or free for rotating according as a set screw w , tapped into one of the brackets in the set, is made to bind or release it; when the worm wheel is fast, the rotating worm will obviously cause traverse of the beam supporting structure, and when it is loose (the worm not now being in motion) the worm wheel may be turned by hand for setting back said structure. As a convenient means for turning the worm-wheel, x is a crank journaled in the bracket in which screw w is tapped and affording a bearing for the worm-wheel, the crank having a clutch-connection y with the worm-wheel and being capable of shifting rearwardly free thereof so as to hang down, idle, when not in use. In Fig. 5 the parts v' , w' , and x' are the same as the parts v , w and x , only here they are arranged in an arm t' depending from the sleeve t , instead of in one of the brackets. In Fig. 6, the several brackets in each set are clamped directly to the front bar, in this case designated d' and arranged to slide longitudinally in the stands c to limits afforded by the collars d^2 on the ends thereof, d^3 being anti-friction bearings supporting said bar d' . The bar has adjustably affixed thereto by means of the set screw d^4 a bracket d^5 in which are arranged parts v'' , w'' and x'' corresponding in construction and functions to parts v , w and x already described. It will be understood that after the warping operation has been completed, leaving the several sections of warp wound helically on the reel, and the clutch device l is shifted so that the power is transmitted from shaft g to shafts e for rotating the same and consequently the beams the rotating reel responding to the draft of the beams will, through the chain and sprocket mechanism m , rotate the worms f and through the described means for disconnectively connecting said worms with the sliding structures supporting the beams and comprising the sleeve t (or d') and the brackets o and p impart a traverse to the beams reverse or contrary to that of the warping operation. When the beaming operation has been completed and it is necessary to return the beam carrying structure to the starting point for another beaming operation, the screw w (w' or w'') is released, crank x (x' or x'')

drawn outward so as to clutch the worm wheel, and then rotated so as to cause the worm-wheel to travel along the worm and so 65 reset the said structure.

Having thus fully described our invention, what we claim as new and desire to secure by Letters Patent is:—

1. In combination, the frame, a supporting structure, a plurality of rotary beams having their axes horizontal and journaled in said structure, means to rotate the several beams including a rotary shaft journaled in the frame parallel with the axes of the 75 beams, said structure being movable in the frame parallel with the axes of the beams and relatively to said shaft, and means to simultaneously move said structure.

2. In combination, the frame, a splined 80 shaft and a rotary screw journaled in the frame parallel with each other, a plurality of rotary beams, a sliding structure movable on said frame parallel with the shaft and screw and including a plurality of pairs of 85 brackets and an elongated member connecting said brackets, each pair of brackets supporting a beam, liberative means to connect said structure with the screw, and gearing, arranged in and movable with one bracket 90 in each pair, operatively connecting said beam with each splined shaft.

3. In combination, the frame, a splined shaft and a rotary screw journaled in the frame parallel with each other, a plurality 95 of rotary beams, a sliding structure movable on said frame parallel with the shaft and screw and including a plurality of pairs of brackets and an elongated member extending parallel with said shaft and screw 100 and having the several brackets each adjustably clamped thereto, each pair of brackets supporting a beam, liberative means to connect said structure with the screw, and gearing, arranged in and movable with one 105 bracket in each pair, operatively connecting each beam with said splined shaft.

4. In combination, the frame having a horizontal fixed guide bar, a longitudinally sliding elongated member supported by the 110 frame, beams, pairs of brackets supporting the beams and secured to said member and slidable on the bar, means to rotate the beams and means to simultaneously move the structure comprising said member and the 115 brackets longitudinally of the bar.

In testimony whereof we affix our signatures in presence of two witnesses.

HUGH WATSON.
CHARLES M. WHRITENOUR.
